Inventor

UNITED STATES PATENT OFFICE.

LOUIS REICHERT, OF SCRANTON, PENNSYLVANIA.

DESIGN FOR A BADGE.

SPECIFICATION forming part of Design No. 21,779, dated August 16, 1892.

Application filed July 2, 1892. Serial No. 438,830. Term of patent 3½ years.

To all whom it may concern:

Be it known that I, LOUIS REICHERT, a citizen of the United States, residing at Scranton, in the county of Lackawanna and State of Pennsylvania, have invented a new and original Design for a Badge, of which the following is a specification.

My invention relates to a design for a badge, the essential features of which are a banner bearing stars and stripes and a circular surface or inclosure bearing the figure of Columbia, crowning the bust of Columbus with a wreath.

My design is described more in detail in connection with the accompanying drawing, which shows a badge embodying my design.

A represents the body of the badge, substantially rectangular or banner-shaped in form, which is bounded at its upper edge by a transverse band or bar B.

C represents a circular inclosure or surface,

within which is represented the figure of Columbia in the act of crowning Columbus with a wreath.

D D represent chains arranged between the band or bar B and the inclosure C.

The surface of the banner-shaped body portion is decorated with stars and stripes, the figure of Columbia within the inclosure is draped with a representation of the national flag, and a shield bearing stars and stripes is arranged within the inclosure.

Having thus described my design, I claim—

The design for a badge, substantially as described and shown.

In testimony that I claim the foregoing as my own I have hereto affixed my signature in the presence of two witnesses.

LOUIS REICHERT.
